The ornamental design for a foot orthotic, as shown and described.

DESCRIPTION

FIG. 1 is a top, front, left perspective view of an orthotic insole, showing our new design, according to a first embodiment that includes wedges and rivets;

FIG. 2 is a top view thereof;

FIG. 3 is a bottom view thereof;

FIG. 4 is a right-side view thereof;

FIG. 5 is a left-side view thereof;

FIG. 6 is a front view thereof; and,

FIG. 7 is a back view thereof.

FIGS. 1-7 are views of a foot orthotic for a left foot. FIGS. 1-7 are also mirror image views of a foot orthotic for a right foot.

The broken lines in FIGS. 1, 4, and 5 depict unclaimed portions of the foot orthotic, and the broken lines form no part of the claim.
